[57] CLAIM

The ornamental design for an automobile body, as shown and described.

DESCRIPTION

FIG. 1 is a top, front and side perspective view of an automobile body showing my new design;

FIG. 2 is a top, side and rear perspective view thereof;

FIG. 3 is a side elevation view thereof, the opposite side being a mirror image thereof;

FIG. 4 is a front elevation view thereof;

FIG. 5 is a rear elevation view thereof;

FIG. 6 is a top, front and side perspective view thereof showing the convertible top in place;

FIG. 7 is a side elevation view thereof showing the convertible top in place, the opposite side being a mirror image thereof;

FIG. 8 is a side elevation view of an automobile body showing a second embodiment of my new design, the opposite side being a mirror image thereof; and,

FIG. 9 is a side elevation view of an automobile body showing the convertible top in place and a second embodiment of my new design, the opposite side being a mirror image thereof.

The appearance of the front and rear views of the second embodiment are the same as in the first embodiment shown in FIGS. 4 and 5.

The broken line showing of certain features, including the wheels and tires throughout the views is for illustrative purposes only and forms no part of the claim design.
